UNITED STATES PATENT OFFICE.

GEORGE DINKEL, OF JERSEY CITY, NEW JERSEY.

MEANS FOR HANGING AND CENTRALIZING OVERDRIVEN CENTRIFUGAL MACHINES.

No. 820,851.

Specification of Letters Patent.

Patented May 15, 1906.

Application filed August 18, 1905. Serial No. 274,666.

To all whom it may concern:

Be it known that I, GEORGE DINKEL, a citizen of the United States, residing in Jersey City, Hudson county, and State of New Jersey, have invented certain new and useful Improvements in Means for Hanging and Centralizing Overdriven Centrifugal Machines, of which the following is a specification sufficient to enable others skilled in the art to which the invention appertains to make and use the same.

My invention relates to apparatus in which the basket is suspended, upon a single (preferably solid) rotatable spindle supported above the basket and centralized by means situated above said point of support, as in my concurrent application, Serial No. 190,803, filed January 27, 1904, and is designed to afford greater leverage and power combined with greater resilience, delicacy, and accuracy in the centralization of the said single rotatable supporting-spindle. To this end the invention includes special spindle-supporting mechanism, in which provision is made for taking up or neutralizing the lateral or side pull of the belt by means of a supplemental antifriction-bearing interposed between the spindle and its support in such manner that the antifriction-rollers upon which the shaft is suspended are relieved of all lateral strain that would otherwise be imparted through the medium of the driving-pulley. The invention consists, further, in a resilient centralizing bearing of special construction arranged above the plane of support of said spindle, as hereinafter more fully described and claimed in detail.

The main difficulty heretofore encountered in overdriven centrifugals in dispensing with the old arrangement of two-spindle machine in which a hollow rotatable spindle carrying the basket and driving-pulley is supported upon a stationary spindle and substituting in lieu thereof a single solid rotatable spindle has been the lack of a suitable centralizing device for the latter. This I obviate in my concurrent application, hereinbefore referred to, by the use of a cylindrical rubber buffer surrounding the single rotatable spindle above the point of support of the latter; but while this arrangement is operative and practical it is subject to limitations and restrictions which I overcome in my present construction. For instance, unless the rubber constituting the cylindrical buffer is perfectly homogeneous throughout its compres-

sion is apt to cause more tension at one place than on another, tending to throw the shaft and basket out of alinement. Furthermore, the cylindrical rubber buffer is necessarily restricted to a position in proximity to the point of support of the rotatable spindle, since the lateral play or movement afforded by it is limited to a comparatively small area. These limitations I obviate by my improved form of centralizing device, which may be applied to the single rotatable spindle a greater distance above the point of support thereof as compared with the cylindrical rubber buffer and in which also provision is made for an extensive and accurate adjustment of the tension on all sides. As a consequence greater leverage may be exercised in centralizing the spindle, resulting in less frictional resistance and requiring less power to drive the machine.

Another advantage attained by my improved construction and arrangement of centralizing device is that it is capable of adjustment to regulate the tension at all times, whether the machine is at rest or in motion, and as each of the several spring-buffers is independently adjustable it is obvious that great accuracy can be attained in centralizing and preserving the alinement of the single rotatable spindle.

In the accompanying drawings, Figure 1 is a central vertical sectional elevation of an overdriven centrifugal supported and centralized according to my present invention; Fig. 2, a plan of the centralizing device; Fig. 3, a sectional elevation taken upon plane of line 3-3, Fig. 2, showing a slightly-modified means for suspending the spindle. Fig. 4 is a sectional elevation, upon an enlarged scale, showing a preferred form of centralizing-collar. Fig. 5 is a view similar to Fig. 3, showing a modification of the invention embodied in a simpler form and arrangement of parts. Fig. 6 is a plan of the structure shown in Fig. 5.

A is a socket-piece or hanger, secured by its flanges *a* to any suitable stationary elevated support and formed at its lower extremity with a semiglobular bearing-cup or socket *a'*, provided with a lining *a*² of Babbitt metal or other antifriction composition. Resting in this concave bearing-surface *a*² is a hemispherical bearing *B*, on which is supported an oil-cup *B'*. Resting upon an annular seat *b*, formed for its support in the oil-cup *B'*, is an annular bearing-plate *C*, formed

upon its upper side with an annular groove *c* for the reception of the antifriction-rollers *d*, which in turn support the annular plate *E*.

In Figs. 1 and 3 the annular bearing-plate 5 *C* is shown as provided with an annular facing *c'*, in which the annular groove *c* is formed, said facing *c'* being replaced when necessary to compensate for wear, the annular plate *C* and its facing *c'* being keyed or 10 otherwise locked together to constitute practically one piece, to all intents and purposes answering the same function as that shown in Fig. 5, and the said annular bearing-plate *C* being keyed to the hemispherical bearing 15 through the medium of the oil-cup *B'* by one or more pins *b* or otherwise held against rotation on said hemispherical bearing *B*, and in like manner the annular plate *E* is keyed by 20 studs *f* or otherwise secured to the bearing-nut *F*.

In the simpler forms (shown in Figs. 3 and 5) the female screw of the bearing-nut *F* engages directly with the male screw-thread *g*, formed on the rotatable spindle *G*, and therefore 25 by sustains the latter through the medium of the plate *E*, resting upon the antifriction-rollers *d*. In Fig. 1 the same result is attained by the engagement of the female screw-thread of the bearing-nut *F* with the 30 male screw-thread *h* on the sleeve *H*, which is formed with a female screw-thread *h'* for engagement with the male screw-thread *g* of the spindle *G*, being locked thereon by a nut *h*. In either construction the bearing-nut 35 *F* is locked in position by a nut *I*, Fig. 1 or, *I*', Figs. 3 and 5, and is formed with an annular seat *f'* for the reception of the annular plate *E*.

The rotatable spindle *G* is preferably, 40 though not necessarily, made solid. To its lower extremity is rigidly secured the basket *J*, held in place upon the threaded end of the spindle *G* by jam nuts *j*. *K* indicates the usual power or brake pulley, secured rigidly 45 to the spindle *G*. The latter may be rotated by power applied in any appropriate manner, as by belts or pulleys, gearing an electric motor having its rotor attached to the spindle *G* and its stator supported in concentric 50 bearings, as set forth in my application, Serial No. 114,358, filed July 5, 1902, or by any mechanical expedient which may be available. In any case, and especially where power is applied by belt to the pulley *K*, I 55 prefer to interpose between the spindle-suspending bearing constituted by the plates *C* and *E* and rollers *d* and the hemispherical bearings *B* a' an antifriction-bearing, which will take up the lateral strain exerted at right 60 angles to the axes of the spindle, thus relieving the suspending-bearings *C* *E* *d* of all tendency to lateral displacement and wear, and thereby greatly reduce the frictional resistance to be overcome in operating the centrifugal. This I accomplish by the use of 65

two horizontally-disposed concentric bearing-rings *L* and *M*, between the opposed vertical surfaces of which are interposed antifriction-rollers *m*, one ring *L* being attached to the hemispherical supporting-bearing *B* through 70 the medium of the oil-cup *B'* and the other ring *M* being secured to an extension of the bearing-nut *F*', as in Fig. 3, or to the sleeve *H*, as in Fig. 1. It will be seen that in either arrangement the inner ring *M* is practically mounted rigidly though indirectly upon the spindle *G*, so that all lateral strain exerted upon or by the spindle will be counteracted or neutralized by the rings *L* and *M* and rollers *m*, which will impart it to 75 the hemispherical bearing *B* and seat *a* and prevent its transmission to the plate *C*, rollers *d*, and plate *E*, so that the bearing-surfaces of the latter will have to sustain only the longitudinal strain or that exerted parallel to the axis of the spindle. It is to be noted particularly in this connection that this lateral antifriction-bearing is interposed in reality between the spindle (the nut *F* or sleeve *H*, as the case may be, being rigidly secured to said spindle) and the hemispherical bearing *B* (since the oil-cup *B'* is rigidly secured to the latter) and that the rings *L* and *M* are concentric to each other and the spindle and occupy the same transverse plane 80 with relation thereto. In other words, this lateral antifriction-bearing is situated and acts at right angles to the spindle-suspending bearing above it, and all lateral pressure exerted by the spindle is borne by the opposed broad surfaces of the concave seat *a* and of the non-rotatable hemispherical bearing *B*, the motion of which latter, as in my concurrent application, hereinbefore referred to, is limited by studs *a* on the hanger *A*, 85 which project into recesses *b* in said bearing, as will be seen by reference to Figs. 1, 3, and 5. While the oscillation of the bearing *B* upon its seat *a* is thus restricted within prescribed bounds and any tendency of the bearing to yield or rotate with the spindle is counteracted, still the extent of play is sufficient for all practical purposes, since very slight space or clearance between the sides of the recesses *b* and the studs *a* will, owing to 90 their proximity to the hemispheric center of support, allow considerable deviation of the spindle *G* from the vertical or plumb.

My improved resilient centralizing device is applied to the spindle *G* above the male 120 screw *g*, and hence above both the supporting-bearings *B* *a* and the suspending-bearing or bearing of rotation, as well as above the basket, and this is an important feature in the combination and arrangement of parts 125 described and claimed herein and distinguishes the invention from centrifugal machines in which a centralizing device is applied to a single solid spindle between the basket and point of support below the bas- 130

ket, as well as from those which a centralizing device is applied below the center of support and between the latter and the basket.

The device consists, essentially, of a bearing-sleeve N , connected with a plurality of radially-arranged resilient buffers or tension-rods T or T' , upon or in conjunction with which are arranged a series of coiled or equivalent springs S , the form or structure of the springs S being obviously of secondary importance provided they afford the necessary resilience and are arranged so as to tend constantly to maintain the bearing-sleeve N or N' , and consequently the spindle G , in a prescribed normal position. Thus cylindrical rubber springs might be substituted for the spiral steel springs shown, if desired, with like result; but metallic springs are preferable under ordinary conditions of use.

The tension-rods T or T' are pivotally connected to the bearing-sleeve N or N' at their inner ends, and their outer extremities pass through stationary guide-posts P , between which and the heads t of the rods are interposed the springs S , substantially as shown in Figs. 5 and 6, in which the simplest form of my resilient centralizing device is illustrated. In this case the springs act as resilient buffers only, which are compressed under excess of pressure and tend constantly to push the spindle into correct alignment. The tension of these springs is regulated by compressing them more or less by means of adjustable end rests p , the shanks of which screw into the guide-posts P , and the extent of motion or play of the rods T or T' inward is regulated by means of adjustable stops or shoulders t' on the outer ends of said rods beyond the guide-posts.

As before stated, in the arrangement shown in Figs. 5 and 6 the springs S tend constantly to push or return the spindle into position. I find by experience that it is desirable in certain cases not only to push the spindle back into position when it deviates therefrom, but also to prevent, in so far as is possible, its swaying from the desired vertical alignment, and hence I arrange supplemental tension or pulling springs S' on the outer extremities of the rods T' and between the guide-posts P and adjustable rests s on the outer extremities of said rods, as illustrated in Figs. 1, 2, and 3, in which views also the inner or push springs S are shown as bearing at their inner ends against adjustable rests s' on the rods T instead of directly against the heads of the latter, as in Figs. 5 and 6. It is obvious that these supplemental tension-springs S' will act in conjunction with the push-springs S on the opposite side of the spindle to maintain the latter in a vertical position.

The adjustable stops or rests s are preferably made in the form of jam-nuts, and the adjustment of the tension of the several springs may be effected while the centrifugal

is in operation, if desired. Furthermore, the tension of each spring may be regulated independent of the others, thus affording delicacy and accuracy of adjustment in centralizing the spindle and maintaining it in such position.

In Fig. 5 the oil-cup is designated B^3 , the upper plate for the rollers is designated E^4 , and the lower plate is designated C^4 .

The bearing-collar may consist of a plain cylindrical sleeve, as shown in Figs. 5 and 6, or it may be provided with antifriction-bearings, as in Figs. 1, 2, and 3, in which case a bearing-ring g^2 is secured to the spindle by means of a retaining-flange g' , and antifriction-rollers r are interposed between said bearing-ring g^2 and an opposed bearing-ring n , seated in the bearing-collar, or any equivalent or well-known mechanical expedient for reducing friction may be interposed between the bearing-collar and the rotatable spindle G .

The placing of the centralizing mechanism a greater distance than heretofore above the bearings of support and rotation increases its leverage with relation to the hemispherical supporting-bearing considered as the fulcrum, and I am thus enabled to more effectively counteract and control the tendency of the basket to gyrate. This I render possible by the use of a relatively large number of tension arms and springs which admit of a considerable degree of lateral play, so that the upper end of the single rotatable spindle may be journaled a sufficient distance above the point of support to insure the minimum of motion, frictional, resistance, and wear. Under these conditions less power is required to drive the machine and its life is prolonged.

It is obvious that, as in the case of my concurrent application No. 190,803, hereinbefore referred to, the hemispherical bearing B and its seat a^2 constitute a "universal joint," by which term, as a matter of convenience, they are designated in the claims.

In using the term "overhung centrifugal apparatus" I mean to designate machines in which the basket or its equivalent is suspended upon a spindle below the point of support of the latter.

It will be noted that the spindle is suspended upon a universal joint and rotatable upon a bearing supported upon and supplemental to said universal joint above the hemispherical center thereof.

What I claim as my invention, and desire to secure by Letters Patent, is—

1. In overhung centrifugal apparatus, the combination of a single spindle suspended upon a universal joint and rotatable upon a bearing supported upon and supplemental to said universal joint the suspension of said spindle being directly on said bearing, said bearing of rotation, said universal joint, and a lateral bearing interposed between said spindle, on one side and said universal joint

- upon the other, one portion of which is mounted rigidly though indirectly upon the spindle and a resilient centralizing device acting on said spindle above said joint and bearing for the purpose described, said centralizing device comprising independently-movable tension-rods.
2. In overhung centrifugal apparatus, the combination of a single spindle suspended upon a universal joint and rotatable upon a bearing supported upon and supplemental to said universal joint above the hemispherical center thereof, and a resilient centralizing device acting on said spindle above said joint and bearing the suspension of said spindle being directly on said bearing, said bearing of rotation, said universal joint, and a lateral bearing interposed between said spindle, on one side and said universal joint upon the other one portion of which is mounted rigidly though indirectly upon the spindle for the purpose described said centralizing device comprising independently-movable tension-rods.
3. In overhung centrifugal apparatus, the combination of a single spindle suspended upon a universal joint and rotatable upon a bearing supported upon and supplemental to said universal joint the suspension of said spindle being directly on said bearing, said bearing of rotation, said universal joint, and a laterally-disposed antifriction-bearing interposed between said spindle on one side and said universal joint on the other for the purpose described.
4. In overhung centrifugal apparatus, the combination of a single spindle suspended upon a universal joint and rotatable upon a bearing supported upon and supplemental to said universal joint above the hemispherical center thereof, the suspension of said spindle being directly on said bearing, said bearing of rotation, said universal joint, and a laterally-disposed antifriction-bearing interposed between said spindle on one side and said universal joint on the other above and in proximity to said joint for the purpose described.
5. In overhung centrifugal apparatus, the combination of a single spindle suspended upon a universal joint and rotatable upon a bearing supported upon and supplemental to said universal joint, the suspension of said spindle being directly on said bearing, said bearing of rotation, said universal joint, and a laterally-disposed means for restricting the oscillation of the universal joint, and a resilient centralizing device acting on said spindle above said joint and bearing and a lateral bearing interposed between said spindle on one side and said universal joint upon the other one portion of which is mounted rigidly though indirectly upon the spindle for the purpose described.
6. In overhung centrifugal apparatus, the combination of a single spindle suspended

upon a universal joint and rotatable upon a bearing supported upon and supplemental to said universal joint, above the hemispherical center thereof, the suspension of said spindle being directly on said bearing, said bearing of rotation said universal joint, horizontally-disposed means for restricting the oscillation of the universal joint, and a resilient centralizing device acting on said spindle above said joint and bearing and a lateral bearing interposed between said spindle on one side and said universal joint upon the other, one portion of which is mounted rigidly though indirectly upon the spindle for the purpose described.

7. In overhung centrifugal apparatus, the combination of a single spindle suspended upon a universal joint and rotatable upon a bearing supported upon and supplemental to said universal joint, the suspension of said spindle being directly on said bearing, said bearing of rotation, said universal joint, horizontally-disposed means for restricting the oscillation of the universal joint, and a laterally-disposed antifriction-bearing interposed between said spindle on one side and said universal joint on the other, for the purpose described.

8. In overhung centrifugal apparatus, the combination of a single spindle suspended upon a universal joint and rotatable upon a bearing supported upon and supplemental to said universal joint, above the hemispherical center thereof, the suspension of said spindle being directly on said bearing, said bearing of rotation, said universal joint, horizontally-disposed means for restricting the oscillation of the universal joint, and a laterally-disposed antifriction-bearing interposed between said spindle on one side and said universal joint on the other above and in proximity to said joint for the purpose described.

9. In overhung centrifugal apparatus, the combination of a single rotatable spindle suspended upon a universal joint said universal joint, and a resilient centralizing device connected directly with the spindle above said universal joint and comprising a bearing-collar encircling said spindle friction-reducing means between said collar and the spindle and a plurality of radially-arranged spring-tension bars, for the purpose described.

10. In overhung centrifugal apparatus, the combination of a single spindle suspended upon a universal joint and rotatable upon a bearing supported upon and supplemental to said universal joint, the suspension of the spindle being directly upon the said bearing, said bearing of rotation, said universal joint and a resilient centralizing device connected directly with the spindle above said bearing of suspension and said universal joint and comprising a bearing-collar encircling said spindle friction-reducing means between said collar and the spindle and a plurality of radially-

arranged spring-tension bars for the purpose described.

11. In overhung centrifugal apparatus, the combination of a single spindle suspended upon a universal joint and rotatable upon a bearing supported upon and supplemental to said universal joint, the suspension of the spindle being directly upon the said bearing, and a resilient centralizing device connected 10 directly with the spindle above said bearing of suspension and said universal joint and consisting of a bearing-collar encircling said spindle friction-reducing means between said collar and the spindle and a plurality of radially-arranged spring-tension bars, together with means for adjusting the tension of the springs, for the purpose described.

12. In overhung centrifugal apparatus, the combination of a single spindle suspended 20 upon a universal joint and rotatable upon a bearing supported upon and supplemental to said universal joint, the suspension of the spindle being directly upon the said bearing, said bearing of rotation, said universal joint, horizontally-disposed means for restricting the oscillation of said universal joint, and a resilient centralizing device connected directly with the spindle above said bearing of suspension and said universal joint and comprising a bearing-collar encircling said spindle friction-reducing means between said collar and the spindle and a plurality of radially-arranged spring-tension bars for the purpose described.

13. In overhung centrifugal apparatus the combination of a single spindle suspended upon a universal joint and rotatable upon a bearing supported upon and supplemental to said universal joint, the suspension of the 30 spindle being directly upon said bearing, said bearing of rotation, said universal joint, a resilient centralizing device connected with the spindle above said bearing of suspension and said universal joint, said centralizing device consisting of a bearing-collar encircling said spindle and a plurality of radially-arranged spring-tension arms, together with an anti-friction-bearing interposed between said bearing-collar and said spindle for the purpose described.

14. In overhung centrifugal apparatus, the combination of a single spindle suspended upon a universal joint and rotatable upon a

bearing supported upon and supplemental to said universal joint, the suspension of the 55 spindle being directly upon said bearing, said bearing of rotation, said universal joint, a laterally-disposed antifriction-bearing interposed between said spindle on one side and said universal joint on the other, and a resilient centralizing device connected with the spindle above said bearing of suspension, universal joint and laterally-disposed antifriction-bearing, said centralizing device comprising a bearing-collar encircling the spindle 60 and a plurality of radially-arranged spring-tension arms for the purpose described.

15. In overhung centrifugal apparatus, the combination of a single spindle suspended upon a universal joint and rotatable upon a 70 bearing supported upon and supplemental to said universal joint, the suspension of the spindle being directly upon said bearing, said bearing of rotation, said universal joint, a resilient centralizing device connected with the 75 spindle above said bearing of suspension and said universal joint, said centralizing device comprising a bearing-collar encircling said spindle and a plurality of radially-arranged spring-tension bars, each provided with two 80 springs, one arranged to push the bar inward centrally and the other arranged to pull the bar outward radially for the purpose described.

16. In overhung centrifugal apparatus, the combination of a single spindle suspended upon a universal joint and rotatable upon a bearing supported upon and supplemental to said universal joint, the suspension of the spindle being directly upon said bearing, said bearing of rotation, said universal joint, a resilient centralizing device connected with the spindle above said bearing of suspension and said universal joint, said centralizing device consisting of a bearing-collar encircling said 95 spindle and a plurality of radially-arranged spring-tension bars, each provided with two springs, one arranged to push the bar inward centrally and the other arranged to pull the bar outward radially, together with means 100 for regulating the tension of the said springs for the purpose described.
